UNITED STATES PATENT OFFICE.

LOUIS P. DISS, OF ILION, NEW YORK, ASSIGNOR TO WYCKOFF, SEAMANS & BENEDICT, OF SAME PLACE.

TYPE-WRITING MACHINE.

SPECIFICATION forming part of Letters Patent No. 678,552, dated July 16, 1901.

Application filed November 14, 1899. Serial No. 736,920. (No model.)

To all whom it may concern:

Be it known that I, LOUIS P. DISS, a citizen of the United States, and a resident of Ilion, in the county of Herkimer and State of New York, have invented certain new and useful Improvements in Type-Writing Machines, of which the following is a specification.

My invention relates to paper-carriages of type-writing machines; and its object is to provide improved means for indicating the position of the carriage.

The improvement is particularly adapted for those machines in which the carriage is provided with an escapement-rack that meshes with a pinion. In the preferred form of the invention I provide the rack with a letter-space scale and fix upon the pinion a series of indexes, so that the indexes revolve together with the pinion as the rack travels endwise and so that when each index reaches its highest rotative point it stands in register with a graduation upon the rack.

The preferred form of the invention is illustrated in the accompanying drawings, forming part of this specification, in which—

Figure 1 is a front view of the top portion of a Remington No. 6 type-writing machine, the carriage being turned up to bring the lower surface of the platen into view and the top plate and type-ring being shown in section. Fig. 2 is a vertical longitudinal central sectional view of the said machine, but with the carriage turned down. Fig. 3 is an enlarged front elevation, including a fragment of the carriage-rack, a scale thereon, and an index-wheel. Fig. 4 is a plan of the parts shown at Fig. 3, and Fig. 5 is an elevation of a modified index-wheel.

The same numerals of reference will be used to designate the same parts in the different views.

1 designates a base, 2 corner-posts, and 3 a top plate or type-ring, which is secured upon the corner-posts, the whole forming a framework for supporting the various portions of the type-writing mechanism.

4 is a carriage provided with guide-rolls 5, which run upon a rail 6, secured to posts 7, rising from the top plate. The carriage is provided with a rearwardly-extending arm 8, having at its back end a yoke, which engages a sleeve 9, loosely mounted upon a rail 10,

the latter being secured to post 11, also rising from the top plate.

A cylindrical platen 12 is secured upon a shaft 13, the latter being provided with hand-wheels 14 and being journaled in the end bars 15 of a platen-frame, the remainder of the frame comprising a front bar 16 and a cylindrical rear bar 17. The platen-frame is pivoted at 18 to a pair of rocker-arms 19, which are pivoted at 20 to the carriage 4. The platen-frame is provided with a grooved front roll 21, (omitted from Fig. 1,) which rides upon a rail 22, suitably supported upon the top plate. Upon this rail is mounted a pointer or an index 23, which cooperates with a scale 24, secured by means of arms 25 upon the front bar 16 of the platen-frame. The platen is provided with pressure-rollers 26, which work in openings 27, formed in a paper-guiding plate or apron 28, which is pivoted to the end bars 15 of the platen-frame by a shaft 29 and which bears upon its forward end a scale 30, which touches the platen and is used in positioning the paper thereon.

The carriage is given a tension toward the left by means of a spring-drum 31, to which is secured at one end a flexible strap 32, the other end of which is suitably secured to the carriage. A pair of arms 33 is pivoted to the carriage at 34 and curve upwardly over the rail 6 and down in front thereof, and a horizontal rack 35 is secured to said arms by means of screws 33^a passing through the rack 35 and engaging said arms. Arranged below said rack and in mesh therewith is a pinion 36, which is fixed to the front end of a horizontal shaft 37, which turns in a bracket 38, fixed upon the top plate. At its rear end the said shaft carries a backing-ratchet housed in a drum 39, and also an escapement-wheel 40. The rack may be swung up about the pivot 34 by means of a lever 41, which is pivoted to the platen-frame at 42 and is provided with a finger-piece 43. Upon being thus released from the control of the pinion and escapement devices the rack and carriage can be moved freely endwise in either direction.

44 and 45 are escapement-dogs working in the teeth of the escapement-wheel 40 and mounted upon a spring-pressed rocker 46, which turns upon an axis 47 and is provided with forward extensions 48, from which hang

hooks 49, that carry a universal bar 50, arranged beneath a series of key-levers 51, each of which is connected by a link 52 to a type-bar 53. Upon the depression of any key the corresponding type-bar is operated and the universal bar 50 is depressed, thus drawing down arms 48 of the dog-rocker and causing the dogs 44 45 to move forwardly. Upon the release of the key the type recedes from the platen, the universal bar and dog-rocker resume their normal positions, and the escapement-wheel advances one tooth, permitting the carriage to be moved a letter-space distance by the spring-barrel 31.

15 The hereinbefore-described mechanism is common in the Remington No. 6 type-writing machine.

I provide the rack 35 with suitable letter-space graduations, preferably by fastening upon the rack a sheet-metal scale 54 by means of small screws 55, which engage threaded holes formed in the heads of the screws 33^a. An index-wheel 56 is rigidly secured to the pinion 36 by means of a screw 57, a collar 58 being disposed between the index-wheel and the pinion in order to position the index-wheel in front of the scale 54. The index-wheel preferably comprises a series of equidistant indexes or points 56^a, the uppermost one of which always registers with a graduation upon the scale 54. The said points are preferably equal in number to the teeth of the pinion 36, and the rack-teeth are preferably arranged at letter-space intervals. Rotative adjustment of the index-wheel relatively to the pinion is permitted by the screw 57. The index-wheel may be constructed in a variety of ways. For example, it may be made in the form of a circular disk, the face whereof may be provided with a series of radial graduations adapted to coöperate with the scale 54, as shown at 56^b, Fig. 5.

When the platen-frame is down in working position, the front scale 24 and index 23 indicate the position of the carriage. When the platen-frame is swung up, as at Fig. 1, the platen-scale 30 is brought into view, and by reference thereto the operator can determine the position of any printed letter upon the paper, and upon referring to scale 54 and index-wheel 56 he can position the carriage at any desired point by moving the carriage until the desired graduation registers with the topmost index 56^a of the star or index wheel. The graduations on scale 54 read from left to right, the same as those upon the platen-scale 30, and preferably the marks upon the scale 54 are directly below or in line with the corresponding marks upon the platen-scale 30, or, in other words, whenever the carriage is arrested by the escapement mechanism in position to receive another type-impression the corresponding graduations upon the two scales 30 and 54, as well as the axis of the pinion 36, lie in the same vertical plane as the printing-center.

It will thus be seen that I have provided a

simple, cheap, and efficient index which is adapted to be adjustably supported by means of a single screw and which, owing to its solid 70 and simple construction and arrangement, is not liable to become accidentally bent or moved out of true position.

It is not essential that the index-wheel be secured to an escapement-wheel pinion or 75 that it be arranged in the same vertical plane as the printing-center so long as it is adapted to rotate during the letter-spacing movements of the carriage.

Inasmuch as the teeth of the pinion may 80 correspond in number and position to the points of the star-wheel and at the cessation of each letter-space movement of the carriage one tooth of the pinion may stand vertically and in register with a graduation of 85 the scale 54, it will therefore be understood that the said pinion in itself may be made to constitute a rotatory star-wheel or multiplicative index to coöperate with the said rack for notating the position of the paper-carriage 90 while the latter is in its upturned position and so that when the carriage is turned down the point previously selected for the type-impression may by the downward motion of the carriage be brought at once over the 95 printing-center of the machine in order that the next impression may be made at the desired point upon the paper without further adjustment. While the pinion may thus serve the same purpose as the star-wheel, 100 nevertheless I prefer to use the separate rotatory device 56 in lieu thereof, for the reason that it may be made larger than the pinion and so that its points or graduations will reach or come nearer to the graduations upon 105 the rack 54, and thus make it easier for the eye to note the position of the carriage. A further reason for preferring the star-wheel lies in the fact that the points of the latter may be made sharper than those of the teeth 110 of the pinion, and hence register more clearly with the graduations of the scale than would the necessarily wider or more blunt teeth of the pinion.

It will also be noted that I have combined 115 with platen-scale 30, rack 35, and pinion 36 a scale upon said rack whose graduations are in line with the scale 30 and a rotatory pointer adapted to coöperate with the scale on the rack, the pointer being arranged in a vertical plane passing through the axis of the pinion.

It will be seen that the scale 54 may be readily secured to the carriage and that the index-wheel 56 may be readily attached to 125 the pinion of an old machine, and also that these parts may be placed upon machines hereafter produced without the necessity of making expensive changes in the patterns and special tools employed in their manufacture.

What I claim as new, and desire to secure by Letters Patent, is—

1. In a type-writing machine, the combina-

tion with a platen-frame adapted to swing up to exhibit the writing, and with a suitable scale, as 30, arranged in proximity to the platen, of a companion scale, as 54, having 5 graduations in line with those of scale 30, and adapted to be brought into view when the platen-frame is swung up, and a suitable rotatory index-wheel arranged upon the machine-frame and adapted to coöperate with 10 the last-mentioned scale, whereby the platen-frame may while swung up be positioned accurately at any desired point in its travel.

2. In a type-writing machine, the combination of a carriage having a scale, a scale extending 15 longitudinally of the carriage and corresponding with the first-mentioned scale, and a wheel arranged in proximity to the scale and having suitable points or graduations thereon adapted to coöperate with the 20 scale to position the carriage, and means for rotating said wheel during the letter-space movements of the carriage.

3. In a type-writing machine, the combination with a carriage, of a rack fixed thereon 25 and provided with suitable letter-space graduations, a pinion arranged in mesh with said rack, an index-wheel secured to said pinion, and a scale secured to the carriage in proximity to said index-wheel.

30 4. In a type-writing machine, the combination with a carriage, of a rack secured thereon, a scale secured to the rack, a pinion arranged upon the frame of the machine in mesh with said rack, and a star-wheel secured to the 35 pinion in proximity to said scale, whereby the points upon said star-wheel coöperate with said scale to indicate the position of the carriage.

5. In a type-writing machine, the combination 40 of a carriage, a rack thereon, a scale arranged upon said rack, a pinion arranged upon the frame of the machine in mesh with said rack, an escapement-wheel of the letter-space mechanism connected to said pinion, 45 and a pointed index-wheel secured upon the pinion in proximity to said scale.

6. In a type-writing machine, the combination 50 with a carriage, a platen-frame mounted thereon so that it may be swung up to exhibit the writing, and a rack secured upon said carriage, of a scale arranged upon the rack, a pinion arranged in mesh with said rack and connected to an escapement-wheel, and a star-wheel secured to said pinion and 55 adapted to coöperate with said scale, whereby the carriage may be accurately positioned while the platen-frame is swung up.

7. In a type-writing machine, the combination 60 with a carriage, a platen-frame thereon adapted to be swung up to exhibit the writing, a scale, as 24, upon the front of said platen-frame, an index as 23 upon the machine adapted to coöperate with said scale, and a scale as 30 arranged in proximity to the platen so as 65 to be brought into view when the platen is swung up, of a scale as 54 arranged upon the

carriage and also adapted to be brought into view when the carriage is swung up, a rack arranged upon the carriage, a pinion as 36 arranged in mesh with said rack, an escapement-wheel connected to said pinion, and a star-wheel secured to turn with said pinion in proximity to said scale 54.

8. In a type-writing machine, the combination 70 of a series of type-bars arranged in a circle, a platen-frame adapted to travel over said types, an escapement-wheel of the letter-spacing mechanism arranged in rear of the types, a shaft for said escapement-wheel extending forwardly to a point over a portion of said 80 type-bars, a pinion carried upon the forward end of said shaft, a rack connected to the platen-frame and arranged in mesh with said pinion, a scale arranged upon said rack, and an index carried by said pinion.

9. In a type-writing machine, the combination 85 of a series of type-bars arranged in a circle, a platen-frame adapted to travel over said types, an escapement-wheel of the letter-spacing mechanism arranged in rear of the types, 90 a shaft for said escapement-wheel extending forwardly to a point over some of said type-bars, a pinion carried upon the forward end of said shaft, a rack connected to the platen-frame and arranged in mesh with said pinion, a scale arranged upon said rack, and an index-wheel fixed upon said pinion.

10. In a type-writing machine, the combination 95 with a platen-frame constructed to be swung up to exhibit the writing and with a scale arranged in proximity to the platen and swinging therewith, of a second scale constructed to travel with the carriage and extending longitudinally thereof and adapted to be brought into view when the platen-frame 105 is swung up, and a rotatory toothed wheel arranged upon the machine-frame and constructed to coöperate with the last-mentioned scale for indicating the position of the carriage.

11. In a type-writing machine, the combination 110 with a carriage, of a rack arranged thereon, a pinion arranged in mesh with said rack and connected to carriage-escapement devices, the axis of said pinion being disposed 115 in the same vertical plane as the printing-center of the machine, a scale so arranged upon said rack that at the completion of any letter-spacing movement the corresponding graduation upon said scale lies in the same 120 vertical plane as the axis of said pinion, and an index for said scale arranged to register with a graduation thereon in said vertical plane.

Signed at Ilion, in the county of Herkimer 125 and State of New York, this 9th day of November, A. D. 1899.
